BLOCK INDICATION APPARATUS FOR CENTRALIZED TRAFFIC CONTROL SYSTEMS OF THE NORMALLY INACTIVE REVERSIBLE CODED TRACK CIRCUIT TYPE

Frank T. Pascoe, Carnegie, and Arthur L. Jerome, Edgewood, Pa., assignors to The Union Switch & Signal Company, Swissvale, Pa., a corporation of Pennsylvania

Application August 13, 1946, Serial No. 690,218

6 Claims. (Cl. 246—3)

1

Our invention relates to railway traffic controlling apparatus, and more particularly to improved means for controlling the occupancy indication means in an absolute permissive block signaling system of the centralized traffic control type in which the signals are controlled in accordance with traffic conditions by a normally inactive system of coded reversible track circuits.

An object of our invention is to provide improved means for controlling the occupancy indication lamp for a single track stretch so that it will cause the occupied indication to be displayed only when the track stretch is occupied.

A further object of the invention is to provide improved means of the type described which is arranged so that the occupied indication will not be displayed temporarily because of differences in the order of transmission of indication codes from the field stations of the centralized traffic control system at opposite ends of the stretch or because transmission of these indication codes is deferred or delayed for an interval.

Another object of the invention is to provide improved means of the type described which is arranged so that the occupied indication is certain to be displayed when the stretch is occupied.

A further object of the invention is to provide improved means of the type described for use in connection with a track stretch where the block clear indication is at times provided from one end and at other times is provided from the other end of a stretch, the equipment being arranged so that after a clear block indication has been sent to the office from the station at one end of the stretch, and a signal clear control code is thereafter transmitted, the clear block indication at the office will be maintained until an indication is transmitted to the office from the station at the other end of the stretch showing that the stretch is clear or that a train has entered the stretch.

Another object of the invention is to provide improved means of the type described which is arranged so that it will not interfere with the interlocked traffic control circuits in the C. T. C. machine which are governed by the block indication codes transmitted from the field stations.

Other objects of the invention and features of novelty will be apparent from the following description taken in connection with the accompanying drawings.

We shall describe one form of railway traffic controlling apparatus embodying our invention and shall then point out the novel features thereof in claims.

2

In the drawings Figs. 1A and 1B, when placed together with Fig. 1A at the left, form a diagram of a stretch of single track railway equipped with a coded track circuit signaling system of a type with which the block indication means provided by this invention is adapted to be employed, and Fig. 2 is a diagram of the circuits in the C. T. C. machine at the control office for controlling the wayside equipment shown in Figs. 1A and 1B and for indicating at the office the nature of traffic conditions in the stretch.

In practicing our invention we provide additional stick circuits for the block indication relays at the office. These stick circuits are arranged so that upon transmission of a signal clear control code the block indication relay which is governed from the exit end of the stretch for the established direction of traffic will not release upon receipt of an occupied block indication code from the associated field station but will remain picked up until the block indication relay which is governed from the field station at the other or entrance end of the stretch is picked up, or until the indication relay for the detector section at the entrance end is picked up to show that a train has entered the stretch. The block indication relays control the block indication lamp so that the occupied indication is displayed when and only when both block indication relays are released.

In the accompanying drawings, in order to illustrate our invention in a simple manner we have shown it applied to a specific system of the type referred to, namely, that disclosed in Letters Patent of the United States, No. 2,344,333, issued March 14, 1944 to James J. Van Horn for Railway Traffic Controlling Apparatus, which patent was reissued as No. 22,780, on August 13, 1946. It will be understood, however, that our invention is not limited to use with this system but can readily be applied to other systems of the same general nature. To facilitate an understanding of our invention, we have employed reference characters similar to those of this patent, that is to say, each relay shown herein which corresponds to one shown in the patent is identified by the same reference character.

Referring to Figs. 1A and 1B of the drawings there is shown therein a stretch of single track railway extending between two passing sidings and provided with wayside signal apparatus for authorizing traffic to move in one direction through the stretch at times and to move in the other direction at other times. In this application only the portions of the wayside apparatus essential to the understanding of this invention

have been shown and the remainder of the equipment may be arranged as shown in the above-identified patent to James J. Van Horn.

The equipment at the left-hand or west end of the single track stretch includes a C. T. C. system field station unit designated Station 1-2, and the equipment at the right-hand or east end of the stretch includes a C. T. C. system field station unit designated Station 3-4.

The field station units are connected with the office over a pair of line wires, not shown, by a code communication system which may be of the type shown in Letters Patent of the United States No. 2,229,249, issued January 21, 1941 to L. V. Lewis for Remote Control Systems.

Consideration of the detailed mode of operation of the code communication system is not needed for an understanding of our invention and it is deemed sufficient to point out that one or more field stations are provided at each end of each track stretch to be controlled and that coding units are provided at the office and at each field station and are connected by a pair of line wires, not shown, over which control codes are transmitted at times to a selected field station, and at other times indication codes are transmitted over the same line wires to the office without interference. Transmission of each code includes the temporary establishment of a plurality of communication channels, such, for example, as seven, between the office and a station to position a group of relays.

Each code includes a distinctive code call by means of which a selector relay 1-2S or 3-4S, at the office and a similar relay, not shown, at one station only is energized to effect temporary establishment of seven communication channels between the office and the station. The different stations have different code calls, consequently the selector relays for different stations or panels are not energized at the same time, and the same channels provide communication at different times with all of the stations.

The explanation of this invention requires only two channels employed in the transmission of control codes and two channels employed in the transmission of indication codes, and in order to simplify the disclosure other channels and related apparatus have not been shown.

The channels employed in the transmission of control codes are designated 1 and 4, and the channels employed in the transmission of indication codes are designated 9 and 10.

It is to be understood that the system of our invention is made up of a number of unit portions generally similar to the one shown in the drawings, but as the invention may be fully understood from one such portion, only one has been illustrated in the drawings.

The office and field stations as well as the intermediate signal location are each provided with a suitable source of direct current, such as a storage battery, not shown, the terminals of which are designated B and C in the drawings.

In most cases in the drawings the relay contacts are located directly under the winding of the relay, but in some cases in order to simplify the drawings, relay contacts are separated from the relay winding and in these instances the relay with which the contacts are associated is designated by appropriate reference characters placed above the contacts.

The equipment at each field station includes a starting relay, not shown, which responds to a change in position of any of the associated indi-

cating relays to provide connection from terminal B of a source of current to the indication channels to effect delivery of indication codes over the line wires during the time that a delivery relay D at the office is energized to thereby position a group of indication relays in accordance with the condition of energization of the indication channels. The circuits for energizing the starting relays at the field stations are arranged in the manner shown in detail in the above-identified patent to Lloyd V. Lewis. These circuits have been omitted in order to simplify this disclosure.

The indication relays at the office governed from the field station 1-2, at the left-hand or west end of the single track stretch, include a track indication relay 1TK, Fig. 2, which controls a lamp, not shown, in the track diagram of the control machine to indicate the occupancy of a short detector section 1T, Fig. 1A, containing the track switch at that end of the stretch, the relay 1TK being controlled by the track relay 1TR for the track section 1T; and a block indication relay 2WTK which is governed by traffic conditions in the single track stretch as hereinafter explained in detail. A track indication relay 3TK and a block indication relay 4ETK at the office are governed in a similar manner through the field station 3-4 at the right-hand end of the single track stretch.

The block lamp 2-4BKE in the track diagram of the control machine is governed by relays 2WTK and 4ETK, and also by traffic relays 4EFK and 2WFK, as hereinafter explained, so as to be lighted when the stretch is occupied.

The signal levers 2SIG and 4SIG on the panel of the control machine of Fig. 2 are the usual three-position levers for the code control of the signal control relays at the field stations at the opposite ends of the stretch. A two-position traffic lever 2-4TFK is also mounted on the panel of the C. T. C. machine and governs a master directional polarized relay 2-4LP to thereby control the transmission of control codes to govern the traffic control relays at the field stations at the ends of the stretch and thus control the coded track circuit apparatus to cause it to prepare the single track stretch for traffic in one direction or the other.

The relay 2-4LP has associated therewith traffic indication relays 2WFK and 4EFK which are stick repeaters of the block indication relays 2WTK and 4ETK as hereinafter explained.

The signal lever 2SIG has associated therewith three stick relays 2LG, 2RG and 2NG. Relays 2LG and 2RG are signal clearing relays which pick up to cause code elements for clearing signal 2L or 2R to be included in a control code, the transmission of which follows the movement of lever 2SIG to the corresponding left-hand or right-hand reverse position, while relay 2NG is a release relay which picks up to cause elements for restoring the signal to stop to be included in a control code transmitted after lever 2SIG has been restored to its normal center position. Relay 2NG causes relay 2RG or 2LG to release when an indication code indicating the return of the signal to stop is received, and then releases.

The signal lever 4SIG has associated therewith two signal clearing relays 4LG and 4RG and a release relay 4NG, which function similarly. The relays 2NG, 2LG, 2RG, 4NG, 4LG and 4RG are controlled substantially in the same manner as are the relays 2-4FL and 2-4FLO, shown and described in our application for Letters Patent

of the United States, Serial No. 592,947, filed May 10, 1945, now Patent No. 2,528,073 dated October 31, 1950.

The traffic lever 2—4TFK is preferably of the push-turn type such as is shown in Letters Patent of the United States No. 2,289,736, issued July 14, 1942, to C. S. Snavely and R. H. Zetwo.

The push buttons 1—2STB and 3—4STB are the starting buttons for operating the usual code starting relays 1—2ST and 3—4ST by means of which control codes are initiated and the corresponding stations selected. Each starting relay when energized initiates a control code as described in Lewis Patent No. 2,229,249 including a code call for energizing a selector relay S for the same panel. Each selector relay when energized releases the associated starting relay and connects terminal B of a local source of energy to selected ones of the control channels in accordance with the position of the contacts of relay 2—4LP and of relays 2RG and 2NG or 4LG and 4NG.

The equipment is arranged so that when energy is applied to channel 1 and a control code is transmitted to a field station, the traffic control relay WFSR or EFSR at that station is operated to condition the wayside apparatus to make that end an exit or a leaving end. Similarly, the equipment is arranged so that when energy is not applied to channel 1 and a control code is transmitted to a field station, the traffic control relay is operated to condition the wayside apparatus to make that end of the stretch an entrance end so that the signal at that point may be controlled by the wayside circuits on operation of the associated signal control relay.

The equipment is also arranged so that when energy is supplied to the code channel 4, and a control code is transmitted to a field station, a signal control relay RHSR or LHSR at that station is operated to render the signal subject to the control of the wayside circuits. When energy is not supplied to the code channel 4 governing a signal control relay, and a control code is transmitted to a field station, the signal control relay at that station is operated to keep the signal at stop irrespective of the condition of the wayside circuits.

The equipment at the office includes a repeater relay M3P which is governed as shown in Fig. 2 by the counting relay O8 and the master relay OM of the office coding unit of the Lewis patent in such manner that the relay is normally energized and is momentarily deenergized during the eighth step of a control code.

The equipment is shown in the condition which it assumes when the track stretch is vacant, the signals 2R and 4L are at stop, and the signaling apparatus prepares the stretch for westbound traffic.

Referring to Fig. 2 of the drawings, the contacts of the master directional relay 2—4LP are in their left-hand or normal positions in which they designate westbound traffic in the associated single track stretch. At this time the block indication relay 2WTK is energized by current supplied over its stick circuit which is traced from terminal B of the source over back contact 20 of relay 3TK, back contact 21 of relay 4ETK, front contact 22 of relay 2WTK, back contact 23 of delivery relay O1—2D, winding of relay 2WTK, back contact 25 of relay 4EFK, and normal polar contact 26 of relay 2—4LP to terminal C. Accordingly, contact 27 of relay 2WTK is picked up and interrupts the circuit of the block

indication lamp 2—4BKE and this lamp is extinguished to indicate that the single track stretch between signals 2R and 4L is not occupied.

At this time the westbound traffic indication relay 2WFK is energized by current supplied over both its pick-up and stick circuits which are traced from terminal B over normal polar contact 28 of relay 2—4LP, front contact 29 of relay 2WFK and front contact 30 of relay 2WTK in parallel, back contact 31 of relay 4EFK, and winding of relay 2WFK to terminal C. As relay 2WFK is picked up, its front contact 32 in the circuit of the lamp 2—4BKE is closed so that energy will be supplied to the lamp on release of relay 2WTK.

As traffic indication relay 2WFK is picked up, its contact 33 in the circuits of the windings of the relay 2—4LP is open, but at this time front contact 36 of block relay 2WTK is closed and permits energy to be supplied to the lower winding of relay 2—4LP on movement of the lever 2—4TFK, provided conditions are proper as hereinafter explained.

As traffic indication relay 2WFK is picked up, its contact 42 in the pick-up circuit for relay 4LG is closed and this relay may be picked up as hereinafter explained.

As the contacts of relay 2—4LP are in their left-hand position, contact 38 connects terminal B of the battery to the circuit governed by front contact 39 of selector relay 1—2S for supplying energy to terminal 1 of the office coding unit so that control codes sent to field station 1—2 at the left-hand end of the stretch will pick up traffic control relay 2WFSR, or will maintain it picked up if it is picked up. At this time contact 33 of relay 2—4LP interrupts the supply of energy to terminal 1 of the office coding unit over the circuit governed by front contact 40 of selector relay 3—4S so the control codes sent to field station 3—4 at the right-hand end of the stretch will release the traffic control relay 4EFSR or will cause it to remain released if it is released.

Turning to the wayside apparatus, the relay 2WFSR, Fig. 1A, at the left-hand end of the single track stretch is picked up and is energized by current supplied over its stick circuit. Accordingly, front contact 44 of relay 2WFSR in the circuit of the code transmitter relay 2RTCTM is closed but this circuit is open at contact 45 of a slow release front contact repeater relay 2RTFSA which is picked up as explained below.

Referring to Fig. 1B it will be seen that traffic control relay 4EFSR is released, and that signal control relay 4LHSR, which governs clearing of signals 4LA and 4LC, is also released. Accordingly, energy is supplied over back contact 46 of relay 4LHSR, back contact 47 of relay 4EFSR, and front contact 48 of the track relay 3TR to a code transmitter relay 4LTCTM and its contact is picked up to connect the track battery 4ETB across the track rails through the winding of the track relay 4LTR in the wrong direction to pick up the relay contacts. The energy supplied from battery 4ETB to the track rails feeds over back contact 50 of a code transmitter relay 4RTCTM to the winding of the track relay 4RTR and picks up its contact 51 to supply energy to its slow release front contact repeater relay 4RTFSA. As relay 4RTR is steadily picked up, the code following repeater relay 2—4TM and the slow release back contact repeater relay 2—4BSA of the track relays 2LTR

and 2RTR remain released and energy is not supplied through the decoding transformer so the code detecting relays 2-4HR and 2-4DR are released. At this time the directional stick relays 2WS and 4ES are also released so steady energy is supplied to a code transmitter relay 2LTCTM over the circuit which includes front contact 60 of relay 4RTFSA, back contact 61 of relay 4ES, back contact 62 of relay 2-4HR, and back contact 63 of relay 2WS. Accordingly, the contact of relay 2LTCTM is picked up and connects the battery 2WTB across the track rails through the winding of the track relay 2LTR in the wrong direction to pick up the relay contacts.

The energy supplied from battery 2WTB to the track rails is supplied over the back contact of the code transmitter relay 2LTCTM to track relay 2RTR and picks up its contact to energize a code following repeater relay 2TM, which in turn establishes a circuit to energize the slow release repeater relay 2RTFSA. As relay 2TM is steadily energized, a slow release back contact repeater relay 2RTESA remains released and energy is not supplied through the decoding transformer to the decoding relays 2RCDR and 2RDR and they remain released. Accordingly, energy is supplied over back contact 76 of relay 2RDR, back contact 77 of relay 2RCDR, front contact 78 of relay 2RTFSA, and front contact 79 of relay 2WFSR to terminal 9 of the field station 1-2 so that indication codes sent to the office from this station cause the block indication relay 2WTK to be picked up.

As the stretch is vacant, the track relay 1TR for the detector section 1T is picked up and its contact 80 interrupts the circuit leading to terminal 10 of the field station unit and indication codes sent from this station cause relay 1TK at the office to be released.

Similarly, at the right-hand end of the stretch the track relay 3TR for the detector section 3T is picked up and interrupts the circuit leading to terminal 10 of the associated field station 3-4 and thus causes indication codes sent from this station to release relay 3TK at the office. In addition, at this time, the circuits leading to terminal 9 of field station 3-4 are interrupted so indication codes sent from this station to the office release relay 4ETK.

If the operator wishes to clear one of the signals 4L to permit a westbound train to enter the stretch, he may do so by moving the signal lever 4SIG to its left-hand position and pressing the starting button 3-4STB to pick up relay 3-4ST and initiate transmission of a control code to field station 3-4.

When the office coding unit operates to transmit the station selection steps of the control code for station 3-4, the selector relay 3-4S is picked up, while the relay M8P releases momentarily during the eighth step of the control code, which step occurs subsequent to picking up of relay 3-4S. During the period in which the relay M8P is released and relay 3-4S is picked up, energy is supplied to the signal clearing relay 4LG over the circuit which is traced from terminal B over back contact 82 of relay M8P, front contact 83 of relay 3-4S, contact 84 of lever 4SIG, front contact 42 of relay 2WFK, and back contact 86 of relay 4RG to the right-hand terminal of the winding of the relay 4LG, while the left-hand terminal of the relay winding is connected over back contact 87 of relay 4NG and back contact 88 of relay 03-4D in multiple, and

thence over back contact 90 of relay 3TK to terminal C. When relay 4LG picks up, its contact 91 establishes connection from terminal B to the right-hand terminal of the relay winding to keep the relay energized after relay M8P picks up and relay 3-4S releases.

The relay 4RG is controlled in substantially the same manner as relay 4LG and is picked up when a control code is transmitted to clear signal 4R. The details of the control of relay 4RG are not essential to the understanding of this invention and are omitted to simplify this disclosure.

The relay 4NG is employed when a control code is transmitted to put a signal to stop, and corresponds to the relay 2-4FLO of our application Serial No. 592,947 hereinbefore referred to.

When relay 4LG picks up, a circuit is established over its front contact 92, back contact 93 of relay 4NG, and front contact 94 of relay 3-4S to input terminal 4 of the office coding unit so that the control code sent to field station 3-4 will pick up the signal control relay 4LHSR.

In addition, when relay 4LG picks up, its contact 97 establishes a circuit shunting the contact 23 of delivery relay 01-2D in the circuit of relay 2WTK to prevent release of relay 2WTK on picking up of the contact of the delivery relay. When relay 4LG picks up, its contact 122 interrupts the circuit of relay 2-4LP so even though front contact 36 of relay 2WTK is closed, energy cannot be supplied to the lower winding of relay 2-4LP to move the relay contacts to their right-hand position. Accordingly, during the time in which relay 2WTK is picked up because of the circuit provided by contact 97 of relay 4LG, the relay 2WTK is ineffective to permit energy to be supplied to relay 2-4LP and this relay is certain to maintain the established traffic direction.

When relay 4LHSR picks up, its contact 95 establishes for the relay a stick circuit including back contact 96 of relay 4RHSR, front contact 98 of relay 3TR, and back contact 99 of the field station delivery relay F3-4D.

When relay 4LHSR picks up, its contact 100 interrupts one circuit for supplying energy to the red lamp R of signal 4LA and establishes a circuit governed by the code detecting relays 4LCDR and 4LDR for supplying energy to the signal lamp.

In the drawings, in order to simplify the disclosure, the local signal control circuits are shown diagrammatically and it is to be understood that these circuits may be arranged in the usual manner so that signal 4LA or 4LB will be cleared depending on the position of the track switch at this point.

In addition, when relay 4LHSR picks up, its contact 46 interrupts the circuit for supplying steady energy to the code transmitter relay 4LTCTM and it releases to cut off the supply of energy from battery 4ETB to the track rails and connects relay 4LTR across the track rails.

When the supply of energy from battery 4ETB to the track rails is cut off, the relay 4RTR releases and interrupts the circuit of relay 4RTFSA and it releases with the result that its contact 60 interrupts the circuit traced above for supplying steady energy to relay 2LTCTM. Accordingly, the contact of relay 2LTCTM releases and interrupts the circuit of the battery 2WTB and connects relay 2LTR across the track rails.

When the supply of energy from battery 2WTB

to the track rails is cut off, the relay 2RTR releases and interrupts the circuit of relay 2TM and it releases and interrupts the circuit of relay 2RTFSA. As a result relay 2RTFSA releases and its contact 45 completes the circuit for supplying coded energy to relay 2RTCTM. This circuit is governed by contact 101 which is governed in accordance with the indication displayed by signal 2LA. The control for contact 101 is arranged so that this contact is released when signal 2LA is at stop and so that the contact is picked up when signal 2LA displays its caution or its clear indication. The details of the control of contact 101 are not essential to an understanding of this invention and are being omitted to simplify this disclosure.

In addition, when relay 2RTFSA releases, its contact 78 interrupts the previously traced circuit for supplying energy to terminal 9 of the field station unit 1-2 and indication codes sent from this station to the office would release relay 2WTK if the stick circuit provided by contact 97 of relay 4LG did not keep the relay energized as hereinafter explained.

As a result of operation of relay 2RTCTM by coded energy, impulses of energy are supplied from the battery 2ETB to the rails of section 2T and operate relay 2LTR. During the picked-up periods of the contact of relay 2LTR energy is supplied to a slow release front contact repeater relay 2LTFSA and its contacts are picked up with the result that during the released periods of relay 2LTR energy is supplied over the back contact of the track relay, front contact 102 of relay 2LTFSA and back contact 103 of relay 4RTFSA to relay 2-4TM and its contacts pick up with the result that energy is supplied over its contact 105 to relay 2-4BSA. As a result the relay 2-4BSA picks up and its contact 106 establishes the circuit governed by a contact of relay 2-4TM for supplying energy to the primary winding of the decoding transformer and on continued operation of the relay 2-4TM energy is supplied through the decoding transformer and picks up the relay 2-4HR, and also picks up the relay 2-4DR if the track relay 2LTR is operated by energy of 180 code frequency.

When relay 2-4HR picks up, energy is supplied over its front contact 108 and front contact 109 of relay 2LTSFA to the circuit governed by contact 110 of relay 2-4DR for supplying energy to the yellow or the green lamp of signal 2W. In addition, at this time energy is supplied over front contact 108 of relay 2-4HR and back contact 111 of relay 4RTFSA to the red lamp R of signal 4E.

After relay 2-4HR picks up, energy of 180 code frequency is supplied to relay 4RTCTM over the circuit which includes back contact 69 of relay 4RTFSA, a contact of code transmitter 180CT, front contact 68 of relay 2-4HR, and back contact 69 of relay 4ES.

When relay 2-4HR picks up, energy is supplied over its front contact 112, back contact 113 of relay 4RTFSA, and front contact 114 of relay 2LTFSA to relay 2WS and its contacts pick up.

As a result of the supply of coded energy to relay 4RTCTM this relay causes coded energy to be supplied from battery 4WTB to the rails of section 4T. This energy operates relay 4LTR and during the picked-up periods of the relay 4LTR energy is supplied to the code following repeater relay 4TM and it picks up. During the picked-up periods of the relay 4TM energy is supplied to the slow release relay 4LTFSA and

its contacts pick up with the result that during the released periods of relay 4TM energy is supplied to the slow release back contact repeater relay 4LTBSA. When relay 4LTBSA picks up, its contact 114 establishes the circuit of the primary winding of the associated decoding transformer and energy is supplied through this transformer to pick up the code detecting relays 4LCDR and 4LDR with the result that energy is supplied over front contact 100 of relay 4LHSR, front contact 115 of relay 4LCDR, and front contact 116 of relay 4LDR to the green lamp G of signal 4LA. In addition, when relay 4LDR picks up, energy is supplied over its front contact 118 to terminal 9 of field station unit 3-4 and indication codes sent from this station to the office will pick up relay 4ETK.

As previously stated, when steady energy is removed from the right-hand end of the stretch and the relay 2RTFSA at the left-hand end of the stretch releases, it removes energy from terminal 9 of the field station 1-2 while the starting relay for this field station is operated to prepare the station to transmit an indication code to the office. Similarly, when coded energy is received at the right-hand end of the stretch and picks up relay 4LDR, it establishes a connection to terminal 9 of the field station 3-4 while the starting relay for this field station is operated to prepare the field station to transmit an indication code to the office.

Since the relay 2RTFSA at the left-hand end of the stretch releases before the relay 4LDR at the right-hand end of the stretch picks up, the field station 1-2 will be prepared to send an indication code to the office before the station 3-4 is prepared to do so. However, because of the operating characteristics of C. T. C. systems the stations may not operate to send indication codes to the office in the order in which the stations are prepared to send such codes. Thus under the circumstances outlined above at times station 1-2 will send an indication code to the office before station 3-4 does so, and at other times station 1-2 will not send an indication code to the office until after station 3-4 has sent an indication code to the office. Furthermore, irrespective of the order in which the two stations operate to transmit indication codes to the office, a considerable time interval may elapse between the time of transmission of codes from the two stations.

The indication code sent from station 1-2 to the office after release of relay 2RTFSA would release relay 2WTK if energy were not supplied to this relay by the stick circuit established by front contact 97 of relay 4LG. If relay 2WTK is released by an indication code sent from station 1-2 before relay 4ETK is picked up by an indication code sent from station 3-4, contact 27 of relay 2WTK will establish the circuit of the lamp 2-4BKE before this circuit is interrupted by contact 120 of relay 4ETK. If this should occur, the lamp 2-4BKE would be lighted to indicate occupancy of the stretch even though the stretch is not occupied. This lamp would be extinguished when an indication code is received from station 3-4 to pick up relay 4ETK but the lamp might be lighted for a substantial period before this code is received. This premature lighting of the block indication lamp would be confusing to operators and this system operates to prevent this improper lighting of this lamp, but at the same time insures that it will always be lighted when it should be lighted.

With the circuits provided by this invention, if under the conditions outlined above the indication code is transmitted from station 1-2 to the office before the indication code is transmitted from station 3-4, the relay 2WTK will not release upon picking up of delivery relay O1-2D at the end of the indication code received from station 1-2. Instead it is maintained picked up by the stick circuit which includes back contact 20 of relay 3TK, back contact 21 of relay 4ETK, front contact 22 of relay 2WTK, front contact 97 of relay 4LG, winding of relay 2WTK, back contact 25 of relay 4EFK, and normal polar contact 26 of relay 2-4LP. Accordingly, contact 27 of relay 2WTK continues to interrupt the circuit of the lamp 2-4BKE and this lamp remains dark.

When an indication code is subsequently received from station 3-4 to pick up relay 4ETK its contact 120 opens the circuit of the lamp 2-4BKE so that on subsequent release of relay 2WTK and closing of its back contact 27 in the circuit of this lamp the lamp is not lighted. When relay 4ETK picks up, its contact 21 interrupts the previously traced stick circuit for relay 2WTK and its contacts release so that its back contact 27 in the circuit of lamp 2-4BKE is closed.

When a train governed by signal 4LA or 4LC enters the stretch, the relay 4LTR ceases to operate and relay 4LDR releases and its contact 118 interrupts the supply of energy to terminal 9 of field station 3-4, and the starting relay for this station is operated to prepare the station to send an indication code to the office. When this indication code is received at the office, it releases relay 4ETK with the result that its contact 120 completes the circuit of lamp 2-4BKE and this lamp is lighted to indicate that the stretch is occupied.

When relay 4ETK releases, its back contact 21 in the stick circuit for relay 2WTK is closed but relay 2WTK remains released since the relay stick circuit is open at its own contact 22. Accordingly, relay 2WTK remains released and its contact 27 maintains the circuit of the lamp 2-4BKE.

If a westbound train enters the stretch promptly after one of the signals 4L has been cleared, it may cause release of relay 4LDR, with consequent interruption of the supply of energy to terminal 9 of the field station 3-4, before this station has had an opportunity to transmit an indication code to the office to pick up the relay 4ETK. Because of release of relay 4LDR and consequent interruption of the supply of energy to terminal 9 of the field station unit, indication codes subsequently transmitted from this station to the office will not pick up relay 4ETK. However, when the train passes through the detector section 3T, the track relay 3TR is released and its contact 121 establishes a circuit to supply energy to terminal 10 of field station 3-4 so that indication codes sent from this station pick up relay 3TK at the office.

As explained in the Lewis patent, the field station units are constructed in such manner that after release of relay 3TR to establish the supply of energy to terminal 10 of the field station unit, this unit causes the next indication code sent to the office to be of such character as to pick up relay 3TK even though relay 3TR picks up before this indication code is transmitted. This insures that on entrance of a train into the stretch an indication code will be sent to the office to pick up relay 3TK even though the train is relatively

short and vacates section 3T before an indication code is sent to the office.

After section 3T is vacated and relay 3TR is picked up, an indication code will be sent to the office to release relay 3TK, but this indication code will not be sent until a code has been sent to pick up relay 3TK. On release of relay 3TK its contact in the circuit of relay 2-4LP is closed, but at this time the circuit of the lower winding of this relay is interrupted by contact 36 of relay 2WTK so energy cannot be supplied to relay 2-4LP to move its contacts to their reverse position.

When the indication code is received at the office to pick up relay 3TK, its contact 20 interrupts the stick circuit for relay 2WTK and it releases so that its contact 27 in the circuit of the lamp 2-4BKE is closed. At this time relay 4ETK is in its released position so its back contact in the circuit of the lamp 2-4BKE is closed and the lamp is lighted to show that the stretch is occupied.

In addition, when relay 3TK picks up, its contact 98 interrupts the stick circuit for relay 4LG and it releases with the result that its contact 122 in the operating circuits for relay 2-4LP is closed, but at this time these circuits are interrupted by contact 124 of relay 3TK so the relay 2-4LP cannot be operated.

When a train enters the stretch, contact 98 of relay 3TR interrupts the stick circuit for relay 4LHSR and it releases to prevent reclearing of the signal 4LA or 4LB unless another control code is sent to pick up this relay. In addition, when relay 4LHSR releases, its back contact 46 in the circuit of relay 4LTCTM is closed and when section 3T is vacated so that front contact 48 of relay 3TR is closed, steady energy is supplied to relay 4LTCTM and its contact picks up to cause steady energy to be supplied from the battery 4ETB to the track rails. As the train proceeds through the stretch the steady energy supplied behind the train follows the train and when the stretch is vacated this energy picks up track relay 2RTR to pick up relays 2TM and 2RTFSA, causing relay 2RTFSA to close its front contact 78 in the circuit leading to terminal 9 of field station 1-2. When relay 2RTFSA picks up, the starting relay for field station 1-2 is operated to cause this field station to transmit an indication code to the office which will pick up relay 2WTK. Accordingly, when delivery relay O1-2D picks up at the end of the indication code and connects relay 2WTK to terminal 9 of the office coding unit energy is supplied to relay 2WTK and its contacts pick up so that front contact 22 of relay 2WTK is closed and on release of relay O1-2D the stick circuit for relay 2WTK is completed and the contacts of the relay 2WTK are thereafter maintained picked up by energy supplied over the relay stick circuit.

When relay 2WTK picks up, its contact 27 interrupts the circuit of the lamp 2-4BKE and this lamp is extinguished to show that the stretch is no longer occupied. In addition, when relay 2WTK picks up, its front contact 36 in the circuit of the lower winding of relay 2-4LP is closed and on movement of the traffic lever 2-4TFK energy may be supplied to the lower winding of relay 2-4LP to move its contacts to their right-hand or reverse position if it is desired to prepare the stretch for eastbound traffic. The equipment is now substantially in the condition in which it is shown in the drawings.

If it is desired to change the wayside apparatus to prepare the stretch for eastbound traffic, the traffic lever 2-4TFK is moved to its right-hand position in which its contact 125 establishes the circuit of the lower winding of relay 2-4LP, assuming that this circuit is otherwise complete, and the contacts of relay 2-4LP move to their right-hand position. On this movement of the contacts of relay 2-4LP contact 26 interrupts the stick circuit for relay 2WTK and its contacts release, while contact 28 of relay 2-4LP interrupts the circuit of relay 2WFK and its contacts release with the result that contact 32 interrupts the circuit of the lamp 2-4BKE and prevents lighting of this lamp upon closing of back contact 27 of relay 2WTK. In addition, on release of relay 2WFK its back contact 35 is closed so that as long as relays 4ETK and 2WTK are released energy may be supplied to either of the windings of the relay 2-4LP. This enables the operator to restore the contacts of the relay 2-4LP to their left-hand position to designate westbound traffic, if the operator wishes to condition the stretch for westbound traffic before the wayside equipment completes the change to eastbound traffic.

The traffic lever 2-4TFK is of the push-turn type and during movement of the lever the contacts 126 and 127 establish pick-up circuits for the starting relays 3-4ST and 1-2 ST and thus cause control codes to be transmitted to stations 1-2 and 3-4. As contact 38 of relay 2-4LP is in its right-hand or reverse position, energy is not supplied to terminal 1 during transmission of the control code to station 1-2 and the code sent to this station releases relay 2WFSR so that its contact 79 in the circuit leading to terminal 9 of the field station is open and so that contact 44 of relay 2WFSR establishes the circuit including back contact 129 of relay 2RHSR for supplying steady energy to relay 2RTCTM. Accordingly, relay 2RTCTM picks up and connects battery 2ETB across the track rails, but energy supplied from battery 2ETB does not pick up the relay 2LTR since relay 2LTCTM is picked up and connects battery 2WTB across the rails through the relay 2LTR. As relay 2LTR remains released the relay 2LTFSAs also remains released.

As contact 38 of relay 2-4LP is in its right-hand position, energy is supplied to terminal 1 of the office coding unit during transmission of the control code to station 3-4 so this control code picks up relay 4EFSR. Accordingly, contact 47 of relay 4EFSR interrupts the circuit for supplying steady energy to relay 4LTCTM and connects this relay to the circuit governed by back contact 130 of relay 4LTFSAs for supplying coded energy to relay 4LTCTM with the result that it now supplies coded energy from battery 4ETB to the rails of section 4T. This coded energy causes code following operation of relay 4RTR with the result that relay 2-4TM operates and causes energy to be supplied through the associated decoding transformer to relay 2-4HR. When relay 2-4HR picks up, its contact 112 establishes the circuit including back contact 114 of relay 2LTFSAs and front contact 113 of relay 4RTFSAs for supplying energy to relay 4ES and its contacts pick up so that contact 61 interrupts the circuit for supplying steady energy to relay 2LTCTM and establishes a circuit including back contact 73 of relay 2LTFSAs for supplying coded energy thereto. During the first released period of relay 2LTCTM energy

from battery 2ETB feeds to relay 2LTR and picks up its contact to establish the circuit of relay 2LTFSAs and its contacts pick up so that contact 73 interrupts the supply of coded energy to relay 2LTCTM and its contacts remain released and maintain relay 2LTR connected across the track rails.

In addition, when relay 2LTFSAs picks up, its contact 102 interrupts the operating circuit for relay 2-4TM and it remains released with the result that energy ceases to be supplied through the decoding transformer to relay 2-4HR and it releases to interrupt the supply of energy to relay 4ES and it releases to close its back contact 69 in the operating circuit of relay 4RTCTM. After release of relay 4ES steady energy is supplied to relay 4RTCTM over the circuit which includes front contact 73 of relay 2LTFSAs, back contact 16 of relay 2WS, back contact 68 of relay 2-4HR, and back contact 69 of relay 4ES. This energy picks up contact 50 of relay 4RTCTM to connect battery 4WTB across the rails of section 4T through the winding of relay 4RTR. After relay 4RTCTM picks up, the relay 4RTR remains released and relay 4RTFSAs releases. After battery 4WTB is connected across the rails of section 4T, energy from the battery feeds to relay 4LTR during the first released period of the contacts of relay 4LTCTM. This energy picks up the contact of relay 4LTR to establish the circuit of relay 4TM and it picks up to establish the circuit of relay 4LTFSAs, with the result that contact 130 of relay 4LTFSAs interrupts the circuit of relay 4LTCTM and it remains released and maintains the circuit of relay 4LTR.

In addition, after relay 4LTFSAs picks up, energy is supplied over back contact 118 of relay 4LDR, back contact 131 of relay 4LCDR, front contact 132 of relay 4LTFSAs, and front contact 133 of relay 4EFSR to terminal 9 of the field station 3-4 and the indication codes sent from this station pick up relay 4ETK at the office.

At the other end of the stretch the circuits for supplying energy to terminal 9 of station 1-2 are interrupted and the indication codes sent from this station do not pick up relay 2WTK at the office and it therefore remains released.

When relay 4ETK at the office picks up, its contact 134 establishes the relay stick circuit which includes back contact 136 of relay 2WTK and back contact 137 of relay 1TK.

In addition, when relay 4ETK picks up, energy is supplied to relay 4EFK over the circuit which includes reverse polar contact 28 of relay 2-4LP, front contact 138 of relay 4ETK and back contact 139 of relay 2WFK. This energy picks up the contacts of relay 4EFK and its front contact 140 establishes a stick circuit to keep the relay contacts picked up during subsequent release of relay 4ETK.

When relay 4EFK picks up, its contact 141 in the circuit of lamp 2-4BKE is closed, but at this time this circuit is interrupted by contact 120 of relay 4ETK so the lamp is not lighted.

In addition, when relay 4EFK picks up, its contact 142 in the circuits of relay 2-4LP is open with the result that energy is no longer supplied over back contact 36 of relay 2WTK to the lower winding of relay 2-4LP but because of the operating characteristics of relay 2-4LP the relay contacts remain in their right-hand position. As long as relay 4ETK is picked up, its front contact 144 establishes a circuit over which energy may be supplied to the upper winding of relay 2-4LP

on movement of lever 2-4TFK to its left-hand position.

When relay 4EFK is picked up, its contact 143 in the pick-up circuit for relay 2RG is closed so that on movement of signal lever 2SIG to its right-hand position, and the transmission of a control code to station 1-2 the relay 2RG will pick up to close its front contact in the circuit leading to terminal 4 of the office coding unit. Accordingly, the control code transmitted at this time picks up relay 2RHSR to remove the steady energy from the left-hand end of the track stretch and to establish a circuit to cause signal 2RA or 2RB to clear when coded energy is received over the single track stretch. Also when relay 2RG picks up, its contact 147 establishes a stick circuit for relay 4ETK to keep its contacts picked up until an indication code is received to pick up relay 2WTK or 1TK. As relay 4ETK remains picked up its contact 120 interrupts the circuit of the lamp 2-4BKE and prevents lighting of this lamp until relay 2WTK picks up to interrupt the lamp circuit, or until relay 1TK picks up to show that a train has entered the stretch.

When relay 2RG picks up, its contact 148 interrupts the circuit of relay 2-4LP so that even though front contact 148 of relay 4ETK is closed, energy cannot be supplied to the upper winding of relay 2-4LP to move its contacts to their normal position and contact 38 of relay 2-4LP is certain to maintain the supply of energy to terminal 1 of the office coding unit during transmission of control codes to station 3-4 and thus insures that these control codes will maintain relay 4EFSR picked up.

When eastbound signal 2RA is cleared, the way-side apparatus operates in substantially the same manner as upon clearing of the westbound signal 4LA and a detailed description of the operation of the apparatus is unnecessary.

From the foregoing it will be seen that the improved circuits provided by this invention insure that when a signal is cleared the block indication lamp will not be improperly lighted because of delays in the operation of the equipment in transferring control of this lamp from the exit to the entrance end of the stretch.

In addition, it will be seen that these circuits are arranged so that when control of the block indication lamp is transferred from the exit to the entrance end of the stretch, the indication relay at the office which is governed from the exit end of the stretch surrenders its control of this lamp as soon as the indication relay at the office which is governed from the entrance end of the stretch shows that it is prepared to assume control of the lamp.

These circuits are also arranged so that if a train enters the stretch before an indication code has been sent to the office to cause the control of the indication lamp to be transferred to the indication relay at the entrance end of the stretch, the indication code sent in response to entrance of the train into the stretch will cause the control of this lamp to be transferred to the indication relay which is governed from the entrance end of the stretch.

The block indication relays are employed in the control of the traffic direction designating relay 2-4LP but the improved circuits of this invention which delay release of the block indication relays cannot result in improper supply of energy to relay 2-4LP because the relays which delay

release of the block indication relays also interrupt the circuit of the relay 2-4LP.

Although we have herein shown and described only one form of railway traffic controlling apparatus embodying our invention, it is understood that various changes and modifications may be made therein within the scope of the appended claims without departing from the spirit and scope of our invention.

10 Having thus described our invention, what we claim is:

1. In a centralized traffic control system for a stretch of single track railroad equipped with a communication system for transmitting control codes from a control office to stations at the ends of the stretch and for transmitting indication codes from the stations to the office, said stretch being equipped with a reversible track circuit system which when energized reflects traffic conditions in said stretch, a first and a second indication relay at the office controlled by said track circuit system by indication codes transmitted from one end and from the other end, respectively, in accordance with its direction of energization to indicate the condition of occupancy of the stretch, said track circuit system being normally energized in the direction to control said first indication relay and arranged to have its direction of energization reversed when a control code is issued for authorizing a train to enter the stretch at the end from which said second indication relay is controlled, said system also including a block indication lamp at the office which when lighted indicates the occupancy of said stretch, having an energizing circuit which includes contacts of said indication relays in series arranged so that the circuit is closed only when both relays assume their block occupied positions, the combination with the foregoing apparatus of means for preventing the temporary closing of said lamp circuit during the reversal of the direction of energization of said track circuit system, comprising a signal clearing relay at the office which is operated when said control code for authorizing a train to enter the stretch is issued and which releases when such authorization is cancelled, means controlled by said signal clearing relay and effective as long as such relay is in its operated position to suspend the code control of said first indication relay from its block clear to its block occupied position, and means controlled by said second indication relay for restoring the first indication relay to its block occupied position when said second indication relay is operated to its block clear position.

2. In a centralized traffic control system as claimed in claim 1, a track indication relay at the office governed by indication codes reflecting the condition of occupancy of a detector track section at the end of the stretch from which said second indication relay is controlled, and means controlled by said track indication relay for restoring said first indication relay to its block occupied position in the event the occupancy of said detector section is indicated but the second indication relay is not operated.

3. In a centralized traffic control system as claimed in claim 2, means for restoring said signal clearing relay to its normal position automatically by said track indication relay when an indication code indicating the occupancy of said detector track section is received, and other means for restoring said signal clearing relay to its normal position effective when a code is re-

ceived which indicates that the authorization for a train to enter the stretch has been manually cancelled.

4. In a centralized traffic control system as claimed in claim 1, the combination in which said first and second indication relays are neutral stick relays arranged to be picked up and released by indication codes which reflect the energized and deenergized condition, respectively, of said track circuit system, and in which the circuit for said block indicator lamp includes back contacts of both indication relays in series and the first indication relay has a stick circuit for holding such relay in its block clear position which includes a back contact of the second indication relay and also includes a normally closed code controlled contact bridged by a normally open contact of said signal clearing relay.

5. In a centralized traffic control system as claimed in claim 4, a track indication relay at the office governed by indication codes reflecting the condition of occupancy of a detector track section at the end of the stretch from which said second indication relay is controlled, and means comprising a contact of said track indication relay included in the stick circuit for said first indication relay for opening said stick circuit when a code is received which indicates the occupancy of said detector track section.

6. In a centralized traffic control system as claimed in claim 5, the combination in which said signal clearing relay is arranged to be picked up in response to the transmission of a control code for authorizing a train to enter the stretch at the end from which said second indication relay is controlled, and is arranged to be released automatically by said track indication relay in response to a code indicating the occupancy of said detector track section, and is also arranged to be released in response to an indication code which follows the transmission of a control code for cancelling the authorization for a train to enter the stretch.
